E. C. CLARK & J. ARRUFAT,
PHOTOGRAPHIC CAMERA AND SIMILAR APPARATUS,
APPLICATION FILED DEC. 30, 1915.

1,198,209.

Patented Aug. 29, 1916.

UNITED STATES PATENT OFFICE

ELIZA C. CLARK AND JOSEPH ARNUFAT, OF BINGHAMTON, NEW YORK, ASSIGNEES TO
ANSCO COMPANY, OF BINGHAMTON, NEW YORK, A CORPORATION OF NEW YORK.

PHOTOGRAPHIC CAMERA AND SIMILAR APPARATUS.

1,106,806.

Specification of Letters Patent. Patented Aug. 20, 1915.

Application filed December 22, 1915. Serial No. 33,821.

to all whom it may concern:

Be it known that we, Eliza C. Clark and Joseph Arnufat, both citizens of the United States, and both residents of the city of Binghamton, county of Broome, and State of New York, have invented certain new and useful Improvements in Photographic Cameras and Similar Apparatus, of which the following is a specification.

Our invention relates to the locking devices for the sliding front, or lens-supporting frame of a camera, and it has for its object to provide a construction which shall be exceedingly economical to manufacture, which automatically locks itself when extended, which allows easy sliding movement both forwardly and rearwardly, which eliminates all lost motion between the parts, thus securing absolute rigidity of the camera front and lens, and a construction which is extremely simple, durable and hence particularly adapted to use by amateurs since it is not likely to become disorganized.

The drawings hereto illustrate the parts which constitute the front or lens-supporting frame of the camera and the track or slideway therefor. These parts are usually made of metal, as in the present instance, but they may be made of such material as preferred.

Figure 1 is a front elevation of a frame and its slideway embodying the invention; Fig. 2 is an edgewise view of that which is shown in Fig. 1; Fig. 3 is a plan view of the under side of the bottom plate of the frame and its slideway, showing the locking mechanism and co-acting parts, the slideway being partly in section; Fig. 4 is a sectional view on the line 4-4 of Fig. 3.

In the drawings 1 represents the front frame proper. In the present instance it is made of aluminum, but it may be made of brass, or any other preferred material. In the present instance, also, it is provided at the upper right hand corner with a projection, or ear 2, to which is pivoted the finger 3, as indicated in broken lines. 4 is a brace for the upright portion of the frame, being suitably attached to a base plate 5, the edges 6, 7, of which are bent downwardly and then forwardly so as to admit dovetailed slideway on the plate adapted to engage with the rails 7, 8, of the slide way proper, which in the pres-

ent instance are formed from the suitably bent edges of a plate 9.

The parts which constitute the locking devices are as follows: Two levers 10, 11, are pivoted respectively at 12, 13, to the plate 5, in which plate there are two slots 14, 15, cut; the free or swinging ends of these levers are bent at right angles to the plane of the lever proper and constitute upwardly projecting finger grasps 16, 17, which during the assembling of the device, are passed upwardly through the slots 14, 15, which are made somewhat wider than the thickness of the metal constituting the finger grasps 16, 17, so that the levers are caused to move inward and outward movement upon their respective pivots. 18 is a spring, the free ends 19, 20, of which engage with the lower edges of the levers 10, 11, as shown, normally forcing them outwardly, and the spring and the levers are maintained in suitable position by a confiner plate 21, which is crimped, or otherwise secured, as at 22, to the plate 5 and the ends 17', 18', of the plate 5 overlap and loosely confine the ends 19, 20, of the spring 18, and also the levers 10. On the outer edge of each lever is made a projecting part 23, on the edge of which is beveled off as at 24, see Figs. 1 and 4, which beveled edges are adapted to enter wedge-like into the triangular opening present at the junction of the under side of the plate 5 and the adjacent upper 25 surface of the track rails 7, as illustrated best in Fig. 6.

The operation is obvious. When the operator applies pressure upon the finger pieces 16, 17, forcing them toward one another, the levers will be swung upon their respective pivots 12, 13, the free ends 14 of the spring will be caused to move inwardly and the wedge-like locking edges 19, 20, of the levers will be withdrawn from locking contact between the plate 5 and the track rails; thereupon the front frame may be moved longitudinally of the track rails, either inwardly or outwardly, and it will be found to have remarkably smooth and easy movement. When the front frame has reached the desired position, the operator releases the finger grasps 16, 17, the spring 18 automatically moves the levers outwardly, so that the wedge-like locking surface 19, 20, of 18, shall engage in the recess between the

top plate 5 and the track rails, locking the front frame in position, and it will be found since all lost motion is taken up and since the pressure of the spring is adequate, that the lock will be remarkably rigid and reliable. Furthermore the construction is so simple that its cost is unusually small and its durability great, its reliability unusual and it is not likely to get out of order in the hands of an entirely inexperienced amateur.

15 We have described and illustrated our invention as applied to the sliding front of an ordinary folding camera but we wish it understood that the invention is applicable to a variety of other similar structures, the construction and requirements of which are substantially the same as those above set forth. It will also be obvious to those who are familiar with such matters that modifications may be made in the details of construction and yet the essentials of the invention be retained. We therefore do not limit ourselves to the details described and claimed.

25 We claim:

1. In apparatus of the class stated, the combination of a sliding part, a slideway therefor, spring actuated locking levers pivoted at one end to the sliding part, a laterally presented part upon each lever the outer edges whereof are beveled and thus adapted to enter the joint between the sliding part and the slideway and lock the sliding part thereto, and means upon the levers above the sliding part whereby the actuat-

ing spring therefor may be compressed and the locking levers withdrawn from engagement with the sliding part and slideway.

2. In apparatus of the class stated, the combination of a sliding part, a slideway 40 therefor, locking levers pivoted at one end to the sliding part, a spring interposed between the levers which normally tends to move them outwardly, a laterally projecting part upon each lever adapted to engage 45 the slideway and to lock the sliding part thereto, and means upon the levers whereby they may be moved inwardly against the stress of the spring, and their said locking parts removed from contact with the slide- 50 way.

3. In apparatus of the class stated, the combination of a sliding part, a slideway therefor, locking levers pivoted at one end to the sliding part, a spring interposed be- 55 tween the levers which normally tends to move them outwardly, a laterally projecting part upon each lever adapted to engage the slideway and to lock the sliding part thereto, means upon the levers whereby they 60 may be moved inwardly against the stress of the spring, and their said locking parts removed from contact with the slideway, and a confiner plate which overlaps the free ends of the spring and the levers, thus as- 65 suring their proper relation to each other.

In testimony whereof we have signed our names to this specification.

EZRA C. CLARK,
JOSEPH ARRUFAT.
